SURFACE ORNAMENTATION.

No. 16,954.

Patented Oct. 26, 1886.

UNITED STATES PATENT OFFICE.

FREDERICK MANKEY, OF WILLIAMSPORT, PENNSYLVANIA.

DESIGN FOR SURFACE ORNAMENTATION.

SPECIFICATION forming part of Design No. 16,954, dated October 26, 1886.

Application filed July 1, 1886. Serial No. 206,866. Term of patent 7 years.

To all whom it may concern:

Be it known that I, FREDERICK MANKEY, of Williamsport, Lycoming county, Pennsylvania, have invented and produced a new and original Design for Surface Ornamentation, of which the following is a specification, reference being had to the accompanying photograph, forming part hereof.

My design consists of the quadrangular elevations A, having inclined edges B. C and D are triangular elevations arranged between adjacent elevations A, and separated therefrom by channels E F. In each elevation A appear four triangular openings, G, symmetrically

disposed, as shown. In each triangular elevation C and D are two triangular openings, H.

I claim--

The design for open-work surface ornamentation, substantially as herein shown and described, which consists of the quadrangular elevations A, having openings G, the triangular elevations C and D, having openings H, and the intermediate channels, E and F.

FREDERICK MANKEY.
